JACOB H. HAWES, OF BOSTON, AND GEORGE H. BLISS, OF WEST STOCKBRIDGE, MASSACHUSETTS.

Letters Patent No. 77,282, dated April 28, 1868; antedated April 25, 1868.

IMPROVED BELT-CLASPS.

The Schedule referred to in these Letters Patent and making part of the same.

TO ALL WHOM IT MAY CONCERN:

Be it known that we, JACOB H. HAWES, of Boston, in the county of Suffolk, and State of Massachusetts, and GEORGE H. BLISS, of West Stockbridge, in the county of Berkshire, and State of Massachusetts, have invented certain new and useful Improvements in Belt-Clasps; and we do hereby declare that the following is a full, clear, and exact description of the same, reference being had to the accompanying drawings, making a portion of this specification, in which—

Figure 1 is a plan view of the outermost side of a belt-clasp constructed according to our invention.

Figure 2 is a longitudinal section of the said clasp, showing the manner of using the same.

Figure 3 is a detached plan view of one portion of the same.

Similar letters of reference indicate corresponding parts in all the figures.

The object of this invention is to provide a belt-clasp which may be manufactured at a very moderate cost, and which will not only serve to effectually secure together the ends of the belt, but which may also be very conveniently manipulated in connecting the said ends, and, furthermore, by the employment of which a smooth surface at the inner side of the belt may be insured, in order to avoid any inequality in the movement of the said belt upon the pulley.

The invention consists in a clasp, constructed with external leaves and internal lips, so combined as to clasp the ends of the belt between them; and, furthermore, in a spring-slip, having the lips just mentioned formed thereon, and capable of being readily secured in or detached from the shell of the clasp, the objects named being, by these means, effectually secured.

To enable others to understand the nature and construction of our invention, we will proceed to describe it with reference to the drawings.

A represents the shell of the clasp, formed of a piece of stiff sheet metal, having its edge-portions folded over, as shown at *a*, in a position parallel with and at a suitable distance from its central or back part, *b*, as indicated more clearly in fig. 1, with a space, *a**, between them, the said edge-portions *a*, thus folded over, constituting leaves, the purpose of which will presently herein appear. The central or back part, *b*, of the shell just described, is bulged outward longitudinally at its middle, as shown at *a'*, in order that a longitudinal recess may be formed in the inner side of the said back, for the reception of a slip, *B*, shown more fully in fig. 2, and which consists of a somewhat elastic strip of sheet metal, made and shaped in its cross-section as represented in fig. 2, and with its lateral edges serrated or furnished with teeth, *b'*, the said toothed or serrated edges constituting lips, *b**, which project downward at an angle when the slip is placed within the shell *A*, as hereinafter fully explained.

When the clasp is in use, the two ends of the belt are thrust through the space *a**, and folded inward over the leaves *a*, which being done, this slip *B* is thrust into the shell *A*, and rests in the longitudinal recess, just described, in the inner side of the back thereof, in such position that the two ends *f* of the belt *C* to be joined, being folded inward over the edges of the leaves *a*, as just hereinbefore described, and brought between the said leaves and the toothed or serrated edges of the spring-slip *B*, the elasticity of the said slip will press the said edges downward upon the belt, and, the tension upon the two ends of the belt being equal, the said tension, by drawing upon the aforesaid edges, will spring them slightly downward thus causing them to tightly hold and confine the ends of the belt within the clasp, one-half of the strain exerted upon the clasp by the belt being borne by the lips *b**, and the others by the leaves *a*, over which the ends of the belt are folded, as just hereinbefore set forth.

When it is desired to unclasp or separate the ends of the belt, the slip *B* is pushed out from the shell *A*, whereupon the aforesaid ends may be readily withdrawn from the latter.

What we claim as our invention, and desire to secure by Letters Patent, is—

1. The clasp, constructed with the leaves, *a*, and internal lips, serving conjointly to hold the ends of the belt, substantially as herein set forth.

2. The detachable spring-slip *B*, constructed with the toothed lips *b**, and arranged within the shell of the clasp, substantially as and for the purpose specified.

J. H. HAWES,
GEO. H. BLISS.
